CLAIM

The ornamental design for a plug-in memory device for electronic governor apparatus for agricultural tractor engines, as shown and described.

DESCRIPTION

FIG. 1 is a perspective view of the bottom, front and one side of a plug-in memory device for electronic governor apparatus for agricultural tractor engines showing my new design;

FIG. 2 is a perspective view of the top, front and opposite side thereof;

FIG. 3 is a top plan view thereof;

FIG. 4 is a side elevational view of one side thereof, the opposite side being a mirror image thereof;

FIG. 5 is a bottom plan view thereof;

FIG. 6 is a rear elevational view thereof;

FIG. 7 is a perspective view of the top, rear and one side thereof; and,

FIG. 8 is a front elevational view thereof.
